DRAWBENCH

Earl Knudsen and Howard H. Talbot, Pittsburgh, Pa.; said Talbot assignor to United Engineering & Foundry Company, Pittsburgh, Pa., a corporation of Pennsylvania

Application July 23, 1941, Serial No. 403,678

19 Claims.

(Cl. 205—3)

This invention relates to draw benches, and more particularly to those designed for reducing or shaping a plurality of elongated blanks such as tubes, rods, bars or other shapes simultaneously.

It is among the objects of this invention to provide a draw bench which utilizes independent blank-gripping carriages, which automatically returns to the dies carriages released from blanks that have been drawn through the dies, which is rapid in operation, in which the various blanks do not interfere with each other, and in which undue strain is not placed on the apparatus.

In accordance with this invention each of a plurality of independent blank-gripping carriages is successively disposed in front of a die, such as a tube-reducing die, where it can be clamped to the end of a blank projecting through the die. Means is provided for moving the carriage and its gripped blank forward until the blank leaves the die whereupon the carriage is released from the blank which falls into a trough or the like. The carriage is then returned to a position adjacent the die, preferably below it, from which it is moved to blank-gripping position in front of the die. Most suitably each carriage carries a plurality of pairs of clamping jaws for gripping a plurality of blanks simultaneously. These jaws are at different levels or positions on the different carriages so that the blanks being drawn by the first carriage will not interfere with the carriage behind it. Preferably the carriage-returning means comprises a downwardly and rearwardly inclined track onto which the carriage rolls after being released from the blanks it was drawing. The carriage then is raised from the rear end of the track back to blank-gripping position in front of the dies by suitable elevating mechanism.

The invention is illustrated in the accompanying drawings in which Fig. 1 is a side view of our apparatus; Fig. 2 is an enlarged fragmentary plan view of the die-end of the apparatus; Fig. 3 is a vertical longitudinal section through one of the carriages in front of the dies; Fig. 4 is an end view of a carriage in front of the dies; Fig. 5 is a vertical transverse section through the top of the elevator; Fig. 6 is an end view of one of the carriages that draws metal blanks from the top pair of dies; Fig. 7 is a vertical section of the main track taken on the line VII—VII of Fig. 2; Fig. 8 is an enlarged fragmentary horizontal section of a blank-gripping portion of a carriage; Fig. 9 is a vertical section taken on the line IX—IX of Fig. 8; Fig. 10 is a section taken vertically of a modified carriage; and Fig. 11 is an

enlarged horizontal view of the modified blank-gripping portion of the carriage.

Referring to Figs. 1, 2 and 3 of the drawings, a plurality of dies 1 are mounted in the upright front end of a support 2 that extends forward over an open pit from a foundation. Starting at a point spaced a short distance in front of the dies and slightly below them is a horizontal track 3 having channel-like sides that face each other and form rails (Fig. 7). The upper strand of an endless chain 4 that extends lengthwise of the track is supported by the bottom of the track on which it slides. The chain extends around sprockets 5 and 6 journaled below the track near its ends, and the forward sprocket 6 is driven in any suitable manner.

The track 3 is adapted to receive and guide a tube-gripping carriage 11 having vertical wheels 12 at each end that travel in the track channels, and horizontal wheels 13 that roll against the upper flanges of the channels to center the carriage in the track as shown in Fig. 4. The carriage is provided on top with a cross head 14 having a horizontal opening 15 through each end in line with one of the dies. Each of these openings tapers toward its rear end and slidably receives and guides a pair of jaws 17 (Fig. 2) the front ends of which are loosely mounted in openings in a cross arm 18. The cross arm is also provided with a vertical opening through which an upright lever 21 loosely extends. The lever is pivotally mounted on a horizontal axis in bearings 22 (Fig. 4) integral with the carriage and extends down into the carriage where a cross pin 23 spans its bifurcated lower end (Fig. 3). When jaws 17 are not gripping a tube the upper end of the lever is swung forward a short distance by means of a counterweighted arm 24 attached thereto.

40 Slidably mounted inside of the carriage and projecting from its front end is a long hook 26 having a longitudinal slot 27 therein that receives cross pin 23 at the lower end of the lever, as shown in Fig. 3. When the carriage is in position ready to grip tubes it is supported in front of the dies and in line with the rear end of the track 3 by an elevator 28 that will be described later. When in this position tubes 31 which have had their front ends forged down are pushed 45 into two of the dies on the level of the cross head 14 and between the jaws in openings 15 of that head. The top of lever 21 is then swung rearwardly manually to force the jaws farther back in the wedge-shaped openings 15 whereby to securely grip the tubes. At substantially the same

time fluid under pressure is supplied to a cylinder 32, mounted on the foundation beneath the die support 2, so as to move forward a plunger 33 that engages the rear end of hook 26 as shown in Fig. 3 and pushes it forward while the carriage is retained on the elevator by a latch 28 pivotally mounted in the die support and normally projected into an opening in the carriage by means of an adjustable spring 30. As soon as the front end of the hook drops down and hooks into the forwardly traveling endless chain 4 the carriage is pulled out of engagement with latch 28. In its forward position the rear end of hook slot 27 pulls against cross pin 23 at the bottom of the lever and thereby tends to force jaws 17 more tightly against the tubes. The chain pulls the carriage and the tubes gripped by it forward along track 3 whereby the tubes are drawn through the dies and their diameter reduced accordingly.

Before the carriage reaches the front end of the chain the rear ends of the tubes leave the dies. This materially reduces the backward pull on the carriage so that as soon as the chain has disengaged itself from hook 26 the counterweighted arm 24 swings the upper end of lever 21 forward to release the jaws from the tubes. The released tubes drop down on transverse guard members or skids 36 from which they roll into cradles 37 at the opposite sides of the track as shown in Fig. 7. Each of these skids is in the form of an arm pivoted at the side of the track and extending upwardly toward the center of the track. The skids are normally held in this position by springs 35 so that after they have been pushed aside by the carriage as it moves along the track they will swing back into position across the track.

After hook 26 has been released from the endless chain the carriage is pushed forward onto the inclined front end of the track by the engagement of the chain with a dog 38 pivoted to the bottom of the carriage as shown in Fig. 3. The carriage with its projecting hook rolls down onto an inclined transfer track 41 that is pivoted at its front end on a horizontal axis in a bearing 42. This track is held in its upper position by means of a pivotally mounted fluid pressure cylinder 43, and is provided near its front end with a bumper 44 to stop the carriage and to drive hook 26 back into it. The cylinder 43 is also used to lower the upper or rear end of the transfer track into line with the front end of a rearwardly and downwardly extending return track 46 so that the carriage can roll backwardly by gravity from the transfer track onto the return track until it is stopped by an escapement 47 actuated by a fluid pressure cylinder 48. When this escapement is actuated to release a carriage the latter rolls on down the return track and onto the top of the elevator 29 which, in the meantime has been lowered so that it will be in line with the rear end of the return track. As shown in Figs. 3 and 5 the top of this elevator is provided with channel-like rails 51 that can be aligned either with the return track or with the main track. At the rear end of each elevator rail there is a spring biased stop 52 which arrests the rearward movement of the carriage. The elevator is raised and lowered by a vertical rod 53 connected to a piston in a fluid pressure cylinder 54 standing below the elevator.

As shown in Figs. 3 and 4 there are two levels of dies 1, although there could be more. The carriage 11 shown in these two figures draws tubes through the lower level, while the carriage shown in Fig. 6

is formed for drawing tubes through the upper pair of dies. To permit tubes to be drawn through all of the dies at the same time the upper pair of dies are located between the lower pair, and the cross head and arm of the carriage of Fig. 6 are short enough to fit between tubes being drawn from the lower dies. Consequently, two carriages can be pulled along track 3 at the same time by the chain 4. As the carriages are spaced along the chain the strain is not all concentrated at one point and the shock on the apparatus caused by carriages periodically engaging and leaving the chain is minimized.

Fig. 1 shows a carriage being pulled forward by the chain and drawing tubes through the top pair of dies, while resting on elevator 29 in front of the dies is another carriage that has just been attached to tubes projecting from the lower pair of dies in readiness to hook onto the chain also. The carriage that drew the preceding set of tubes from the lower dies has released them and is shown rolling down the transfer track 41. The carriage that drew the preceding set of tubes from the upper dies is shown on return track 46 where its travel back to the elevator has been arrested temporarily by escapement 47. As soon as the carriage shown on the elevator in front of the dies has been pulled onto track 3, the elevator will be lowered for receiving the lower carriage from the escapement and for then raising it into tube-gripping position.

In the embodiment of the invention shown in Figs. 8 and 9 the jaws 17 slide in a cross head 56 on both sides of an opening 57 that is open at its top as well as at its ends. With this construction the front end of a tube can be projected from a die before the carriage is elevated, and then the carriage raised to cause the jaws to move up opposite sides of the tube to gripping position.

The modified form of carriage 11a is adapted to be received in tracks 3 in a fashion similar to that with respect to carriage 11 described heretofore. Carriage 11a is provided with vertical wheels 12a at each end that travel in the track channels and horizontal wheels, not shown, similar to those of carriage 11 which roll against the upper flanges of the channels to center the carriage in the track. The carriage is provided on top with a crosshead 14a having a horizontal opening through each end in line with the dies. Each of these openings tapers toward its rear end and slidably receives and guides a pair of jaws 17a, the front ends of which are provided with hooks 42a for engaging the recessed portion of members 43a. The members 43a are secured for sliding movement on the projection 45a of crosshead 14a by means of studs 18a passing through the outer edge of the projecting portion and threaded into a boss at the lower portion of member 43a positioned in the slot 46a. A spring 22a encircling the stud is secured in place by means of nut 21a threaded on the opposite end of the stud, the spring being compressed between the nut and projection 45a at the front end of slot 46a. Engaging the outer edges of members 43a are the outwardly projecting arms of a pivotally mounted lever 26a. This lever is secured for pivotal movement at its mid-section by a bolt 19a passing therethrough and into a member 47a slidably mounted on ways provided on the projecting portion of crosshead 14a. Pinned at one end to a boss 48a of member 47a is a strut 36a having pinned at its opposite end a lever 34a. This lever, pivotally mounted at 35a on the piston rod 49a, is provided with a gripping-jaw ad-

Justing handle 37a at one end and a pin 23a at the other which passes through a longitudinally extending slot 27a of hook 26a.

Secured to the piston rod 49a is a piston 38a received in cylinder 39a firmly mounted on the frame. A bolt 51a is passed through a clearance hole drilled in the bottom portion of cross head 14a and threaded into the end of the piston rod 49a encircled by a spring 52a. A needle valve 41a for bleeding the compressed air from the cylinder and a check valve 40a for permitting air to be drawn into the cylinder when the piston is returned to its normal idle position are in communication with the cylinder at the head end thereof.

In order to cause the hook 26a to engage one of the links of the continuous moving chain 4, a piston provided with a rod 33a is actuated to engage the hook 26a to push it forward. As soon as the portion of the hook at the end of the slot 27a contacts the pin 23a, the hook drops down and engages one of the links of chain 4. The sudden shock encountered thereby is relieved by means of the piston 38a which moves forward rapidly compressing the air trapped in the cylinder 39a which escapes slowly through the needle valve 41a. When the piston reaches the end of its stroke, the carriage secured to the ends of the tubes by means of jaws 17a then moves forward with the chain 4. The spring 52a compressed by this action returns the piston 38a to its normal idle position when the tubes have passed through the die, thereby permitting the jaws 17a to open by the action of compressed springs 22a to release the opposite ends of the tubes therefrom.

Although this invention has been described in connection with the drawing of tubes, it will be clear that it is equally applicable to the drawing of rods and other shapes.

According to the provisions of the patent statutes, we have explained the principle and construction of our invention and have illustrated and described what we now consider to represent its best embodiment. However, we desire to have it understood that, within the scope of the appended claims, the invention may be practiced otherwise than as specifically illustrated and described.

We claim:

1. A draw bench comprising a blank-gripping carriage adapted to be positioned in front of a die, a traveling endless chain for detachably engaging the carriage to pull it with a gripped blank forward away from the die to a position at which the blank is released from the die and carriage, means for returning the released carriage to blank-gripping position in front of the die and including a track inclined downwardly from the front end of said chain, and means depending from the bottom of the carriage adapted to be engaged by the chain to push the car onto said track.

2. A draw bench comprising a blank-gripping carriage adapted to be positioned in front of a die, means for detachably engaging the carriage to move it with a gripped blank forward away from the die to a position at which the blank is released from the die and carriage, a gravity return track inclined downwardly and rearwardly below said means, an inclined transfer track down which the released carriage travels from said carriage-engaging means to the front end of said return track, and means for elevating the

carriage from the rear end of the return track to blank-gripping position in front of the die.

3. A draw bench comprising a blank-gripping carriage adapted to be positioned in front of a die, means for detachably engaging the carriage to move it with a gripped blank forward away from the die to a position at which the blank is released from the die and carriage, a return track below said means, an inclined transfer track down which the released carriage travels forward from said carriage-engaging means, means for lowering the rear end of the transfer track so that said carriage travels back across it and onto said return track, and means for elevating the carriage from the rear end of the return track to blank-gripping position in front of the die.

4. A draw bench comprising a blank-gripping carriage adapted to be positioned in front of a die, means for detachably engaging the carriage to move it with a gripped blank forward away from the die to a position at which the blank is released from die and carriage, a return track below said means, an inclined transfer track down which the released carriage travels forward from said carriage-engaging means, the front end of the transfer track being pivoted on a horizontal axis, means for raising and lowering the rear end of the transfer track to cause it to register with said carriage-engaging means and said return track, and means for elevating the carriage from the rear end of the return track to blank-gripping position in front of the die.

5. A draw bench comprising a blank-gripping carriage adapted to be positioned in front of a die, means for detachably engaging the carriage to move it with a gripped blank forward away from the die to a position at which the blank is released from the die and carriage, a return track inclined downwardly and rearwardly below said means, means for transferring the released carriage from said carriage-engaging means to the front end of the track, a removable stop associated with said track to arrest the carriage before it reaches the lower end of the track, and means for elevating the carriage from the rear end of the track to blank-gripping position in front of the die.

6. A draw bench comprising a blank-gripping carriage adapted to be positioned in front of a die, means for detachably engaging the carriage to move it with a gripped blank forward away from the die to a position at which the blank is released from the die and carriage, an elevator below the die adapted to raise a carriage to blank-gripping position in front of the die, a gravity return track below said means extending downwardly and rearwardly to the elevator, and means for transferring the released carriage from said carriage-engaging means to the front end of the track.

7. A draw bench comprising a blank-gripping carriage adapted to be positioned in front of a die, a forwardly sliding hook mounted in the carriage, means in front of the carriage for moving it with a gripped blank forward away from the die to a position at which the blank is released, means adjacent the die for pushing said hook forward for engagement by said first-mentioned means, means for moving said hook back into the carriage after the carriage is released from said carriage-moving means, means for returning the released carriage to a position below the die, and means for elevating the carriage with its retracted hook to blank-gripping position in front of the die.

8. A draw bench comprising a blank-gripping carriage adapted to be positioned in front of a die, clamping jaws mounted on said carriage for gripping the ends of a blank projecting from the die, means for detachably engaging the carriage to move it with a gripped blank forward away from the die, a counterweight operatively connected to said jaws and biasing them forward, for automatically releasing the jaws from the blank when the blank leaves the die, means for returning the released carriage to a position in the vicinity of the die, and means for moving the returned carriage to blank-gripping position in front of the die.

9. A draw bench comprising a blank-gripping carriage adapted to be positioned in front of a die, clamping jaws mounted on said carriage, a sliding hook mounted in the carriage and adapted when pulled forward to hold said jaws tightly clamped on a blank, means in front of the carriage for detachably engaging said hook to move the carriage with a gripped blank forward away from the die, counterweighted means operatively connected to said jaws for automatically releasing them from the blank when the blank leaves the die, and means for returning the released carriage to blank-gripping position in front of the die.

10. A draw bench comprising a plurality of independent carriages adapted to be positioned in front of a plurality of pairs of blank-reducing dies disposed at different levels, two laterally spaced sets of clamping jaws mounted on each carriage for gripping a pair of blanks, the jaws on each carriage being at a different level than those on the adjacent carriages, means for detachably engaging the carriages in succession to successively move each carriage with its gripped blanks forward away from the dies to a position where the blanks are released from the dies and carriages, means for returning the released carriages in succession to a position in the vicinity of the dies, and means for successively moving each returned carriage to blank-gripping position in front of the dies.

11. A draw bench comprising a blank-gripping carriage adapted to be positioned in front of a die, a pair of horizontally acting clamping jaws mounted on said carriage for gripping the end of a blank projecting from the front of the die, said jaws being free of any obstruction above the space between them, means for detachably engaging the carriage to move it with a gripped blank forward away from the die to a position at which the blank is released from the die and carriage, means for returning the released carriage to a position below the die, and means for elevating the returned carriage to blank-gripping position in front of the die.

12. A draw bench comprising a blank-gripping carriage adapted to be positioned in front of a die, a forwardly sliding hook mounted in the carriage, means in front of the carriage for moving it with a gripped blank forward away from the die to a position at which the blank is released, means adjacent the die for pushing said hook forward for engagement by said first-mentioned means, means for holding the carriage stationary while said hook is being pushed forward therein, means for returning the released carriage to a position in the vicinity of the die, and means for moving the returned carriage to blank-gripping position in front of the die.

13. A draw bench comprising a blank-gripping carriage adapted to be positioned in front of a

die, a forwardly sliding hook mounted in the carriage, means in front of the carriage for moving it with a gripped blank forward away from the die to a position at which the blank is released, means adjacent the die for pushing said hook forward for engagement by said first-mentioned means, means for holding the carriage stationary while said hook is being pushed forward therein, means mounted on said carriage for absorbing the shock encountered by said hook when engaging said first-mentioned means, means for returning the released carriage to a position in the vicinity of the die, and means for moving the returned carriage to blank-gripping position in front of the die.

14. A draw bench comprising a carriage having independently operable blank-gripping means mounted thereon adapted to be positioned in front of a die, a forwardly sliding hook mounted in the carriage, means in front of the carriage for moving it with a gripped blank forward away from the die to a position at which the blank is released, means adjacent the die for pushing said hook forward for engagement by said second-mentioned means, means for holding the carriage stationary while said hook is being pushed forward therein, means for returning the released carriage to a position in the vicinity of the die, and means for moving the returned carriage to blank-gripping position in front of the die.

15. A draw bench comprising a carriage having independently operable blank-gripping means mounted thereon adapted to be positioned in front of a die, a hook slidably mounted in the carriage, means in front of the carriage for moving it with a gripped blank forward away from the die to a position at which the blank is released, means adjacent the die for pushing said hook forward for engagement by said second-mentioned means, means for holding the carriage stationary while said hook is being pushed forward therein, means for absorbing the shock encountered by said hook when engaging said second-mentioned means, means for returning the released carriage to a position in the vicinity of the die, and means for moving the returned carriage to blank-gripping position in front of the die.

16. A draw bench comprising a plurality of independent carriages adapted to be successively positioned in front of a group of dies, means on the carriages for gripping the front ends of blanks projecting through the dies, means for detachably engaging the carriages to move a plurality of them in succession forward away from the dies along the same path at the same time to a position where the blanks are released from the dies and carriages, the gripping means on each carriage being in a different position relative thereto than the gripping means on the following carriage so that a plurality of carriages can draw blanks through the dies at the same time and thus maintain continuous drawing, and means for returning the released carriages in succession to blank-gripping position in front of the dies.

17. A draw bench comprising a plurality of independent carriages adapted to be successively positioned in front of a group of dies, means on the carriages for gripping the front ends of blanks projecting through the dies, one track in front of the dies for all of the carriages, an endless chain traveling along the track, means for detachably connecting each carriage to the chain in succession for moving a plurality of them for-

ward along the track at the same time to a position where the blanks are released from the dies and carriages, the gripping means on each carriage being in a different position relative thereto than the gripping means on the following carriage so that a plurality of carriages can draw blanks through the dies at the same time and thus maintain continuous drawing, and means for returning the released carriages in succession to blank-gripping position in front of the dies.

18. A draw bench comprising a plurality of independent carriages adapted to be successively positioned in front of a group of dies, means on the carriages for gripping the front ends of blanks projecting through the dies, means for detachably engaging the carriages to move a plurality of them in succession forward away from the dies along the same path at the same time to a position where the blanks are released from the dies and carriages, the gripping means on each carriage being in a different position relative thereto than the gripping means on the following carriage so that a plurality of carriages can draw blanks through the dies at the same time and thus maintain continuous drawing.

25

means for returning the released carriages by gravity in succession to a position below the dies, and means for elevating the returned carriages in succession to blank-gripping position in front of the dies.

19. A draw bench comprising a plurality of independent carriages adapted to be positioned in front of a plurality of blank-reducing dies disposed at different levels and at different lateral positions, a set of clamping jaws mounted on each carriage for gripping a blank, the jaws on each carriage being at a different level and a different lateral position than those on the adjacent carriages, one track in front of the dies for all of the carriages, means for detachably engaging the carriages in succession to successively move each carriage with its gripped blank forward along said track away from the dies to a position where the blank is released from the dies and carriage, and means for returning the released carriages in succession to blank-gripping position in front of the dies.

EARL KNUDSEN.
HOWARD H. TALBOT.
